UNITED STATES PATENT OFFICE.

HUGO PAUL DICK, OF LOWELL, MASSACHUSETTS, ASSIGNOR TO MERRIMACK MANUFACTURING COMPANY, OF LOWELL, MASSACHUSETTS, A CORPORATION OF MASSACHUSETTS.

DESIGN FOR A PILE FABRIC.

Application filed November 26, 1926. Serial No. 19,855. Term of patent 3½ years.

To all whom it may concern:

Be it known that I, HUGO PAUL DICK, a citizen of the United States, residing at No. 48 Gertrude Avenue, Lowell, in the county of Middlesex and State of Massachusetts, have invented a new, original, and ornamental Design for Pile Fabrics, of which the following is a specification, reference being had to the accompanying drawing, forming a part thereof.

Figure 1 is a plan view of a pile fabric showing my new design.

Figure 2 is a cross-sectional view of the same taken on the line A—A, Figure 1.

The vertical dotted lines in the drawing indicate the depressions between the ribs of the pile.

I claim:

The ornamental design for a pile fabric as shown and described.

Dated: November 20th, 1926.

HUGO PAUL DICK.
